UNITED STATES PATENT OFFICE.

RUSSELL HUFF, OF DETROIT, MICHIGAN, ASSIGNOR TO PACKARD MOTOR CAR COMPANY, OF DETROIT, MICHIGAN, A CORPORATION OF MICHIGAN.

MOTOR-VEHICLE.

1,072,851.

Specification of Letters Patent.

Patented Sept. 9, 1913.

Application filed November 23, 1912. Serial No. 733,127.

To all whom it may concern:

Be it known that I, RUSSELL HUFF, a citizen of the United States, and resident of Detroit, Wayne county, State of Michigan, 5 have invented certain new and useful Improvements in Motor-Vehicles, of which the following is a specification.

This invention relates to motor vehicles, and particularly to the form of support for 10 the motor and for the fan that is usually mounted at the front end of the motor in the rear of the radiator.

One of the objects of the invention is to 15 pivotally support one end of the motor from a cross beam of the vehicle frame and to mount the fan bracket above such cross beam so that it partakes of the slight oscillations of the motor about its pivot.

Another object of the invention is to 20 provide a bracket secured to the motor, a pivot between the bracket and a cross beam of the vehicle frame, a fan bracket supported on the pivot bracket, and a locking plate secured between the fan bracket and the pivot 25 bracket for locking the pivot pin in place.

Other objects of the invention will appear 30 from the following description, taken in connection with the drawings, which form a part of this specification, and in which, Figure 1 is a perspective view of the front 35 end of a motor and the contiguous supporting parts of a vehicle frame; Fig. 2 is an enlarged front end view of the pivot bracket and associated parts; and Fig. 3 is a section on the line 3—3 of Fig. 2.

Referring to the drawings, the crank case or supporting base of the motor is represented at 10, and upon this base are mounted the cylinders 11. The front end of the supporting base is in the form of a gear case 12, 40 which houses the gears for driving the cam shafts and other accessory shafts of the motor. These gears also drive a pulley 13, which is shown as arranged at one side of the motor in one of the extended ends of the gear casing 12.

One of the side members of the vehicle frame is shown at 14, and upon this member and the opposite side member is supported a cross beam 15, which forms the front supporting beam of the motor. It 45 will be understood that the rear end of the motor is suitably supported from the vehicle frame, but these parts of the motor are not

shown in this application, as they form no 55 part of the invention, and would only tend to confusion. A bracket 16 is suitably secured to the front end of the motor, as by bolts 17, and it is formed with two separated upwardly extending ears 18, between which 60 the central part of the cross beam 15 passes. The ears 18 and cross beam 15 are connected by a pivot bolt 19, which may be provided with a bearing sleeve 20 to take the wear. By this construction, it will be seen that the 65 front end of the motor is supported entirely through this pivot pin 19 from the beam 15, so that any distortion of the front end of the frame members 14 would not be communicated to the supporting base 10 of the 70 motor. There will therefore be slight relative movement between the motor base and the beam 15, with the center of the pivot pin 19 as an axis. It will be further observed that should the fan bracket, to be 75 hereinafter described, be supported directly upon the beam 15, the pulley 13, in swinging about the axis of the pivot pin 19, would at times be closer to the axis of the fan pulley than at others, so that stretching of the belt 80 would result. To overcome this difficulty, the present invention provides for mounting the fan bracket upon a part of the motor so that the fan bracket, and consequently the fan pulley mounted thereon, will swing with 85 the driving pulley 13, and the distance between the pulleys will remain constant. This construction will now be described.

The ears 18 are formed with upwardly extending lugs 21, which form a support entirely above the beam 15, and upon these lugs is secured a fan bracket 22, as by bolts 23, which bolts are threaded into the lugs 21. The fan bracket 22 supports a fan 24, upon the spindle of which is mounted a 95 driven pulley 25 which is connected to the driving pulley 13 through a belt 26, or any other suitable driving mechanism.

Preferably secured between the bracket 22 and the lugs 21 is a plate 27, having a 100 bent over portion 28 which is positioned over the head of the pivot bolt 19 to prevent the latter from being withdrawn. This forms a lock for the bolt 19 and also forms a supporting pad on the lugs 21 for 105 the bracket 22.

The advantages of the invention have been clearly set forth in the above descrip-

tion, and the operation of the mechanism is believed to be clearly understood therefrom.

Various modifications may be made without departing from the spirit or scope of this invention.

Having thus described my invention, what I claim and desire to secure by Letters Patent, is:

- 10 1. The combination with a motor, of a cross supporting beam, a bracket secured to the motor, a pivot bolt connecting said bracket to said cross beam, a fan mounted on said bracket, and means for driving the fan from the motor.
- 15 2. The combination with a motor, of a cross supporting beam, a bracket secured to the motor, a pivot bolt connecting said bracket to said cross beam, a fan mounted on said bracket, and means at one side of the motor for driving said fan.
- 20 3. The combination with a motor, of a cross supporting beam, a bracket secured to the motor, a pivot bolt connecting said bracket to said cross beam, a fan mounted on said bracket above the cross beam, and a flexible driving mechanism for driving said fan from one side of said motor.
- 25 4. The combination with a motor, of a supporting cross beam, a bracket secured to the motor and having upwardly extending lugs, a pivot bolt extending through said lugs and said cross beam, and a fan bracket supported on said lugs.

5. The combination with a motor, of a supporting cross beam, a bracket secured to the motor and having upwardly extending lugs, a pivot bolt extending through said lugs and said cross beam, a fan bracket supported on said lugs, and a lock for said bolt secured between the fan bracket and said lugs.

6. The combination with a motor, of a cross supporting beam, a bracket secured to the motor and having upwardly extending lugs, a pivot bolt extending through said lugs and said cross beam, a fan bracket supported on said lugs, a fan, and belt mechanism for driving said fan from the side of the motor.

7. In a motor vehicle, the combination with the frame side members and a motor arranged between said members, of a cross beam connecting said side members, a pivotal connection between the cross member and the motor for supporting the latter, a fan bracket mounted on said connection so that it partakes of the movements of the motor about the pivot, a fan on said bracket, and means for driving the fan from the motor.

In testimony whereof I affix my signature in the presence of two witnesses.

RUSSELL HUFF.
